CONTROL SYSTEM.

1,264,354.

Specification of Letters Patent. Patented Apr. 30, 1918.

Application filed August 10, 1915. Serial No. 44,750.

To all whom it may concern:

Be it known that I, CHARLES C. WHITTAKER, a citizen of the United States, and a resident of Wilkinsburg, in the county of 5 Allegheny and State of Pennsylvania, have invented a new and useful Improvement in Control Systems, of which the following is a specification.

My invention relates to control systems 10 for pantograph trolleys and it has special reference to the control of trolleys of the type which are maintained in engagement with the trolley conductor by means of springs and which are actuated into their 15 lowered positions pneumatically.

One of the objects of my invention is to provide a system of the above-indicated character which shall be simple and inexpensive in arrangement; which shall operate 20 with effectiveness and reliability, and which shall be provided with adequate means for insuring that the trolley be actuated to its lowered position when this movement is once initiated.

More specifically, it is an object of my 25 invention to provide a trolley of the class referred to which shall be controlled electrically from the main source of energy (the trolley conductor) and which shall be provided with an electrically-controlled valve 30 for governing the admission of operating fluid to the pneumatic lowering device, said valve being, by reason of its peculiar arrangement of parts, adapted to hold itself 35 open after being temporarily energized, thereby insuring the lowering of the trolley even though the control-circuit energy is cut off by reason of the disengagement of the trolley and the trolley conductor.

Another object of my invention is to provide 40 a simple and effective means for releasing the operating fluid from the lowering cylinder or pneumatic device when the trolley has reached its lowered position.

In a co-pending application Serial No. 44,751, filed of even date herewith by Karl A. Simon and assigned to the Westinghouse Elec. & Mfg. Company, a control system having the same general characteristics 50 is disclosed, in which a pneumatic relay device is employed for controlling the operation of the governing valve, and this pneu-

matic relay depends for its operation upon maintaining a predetermined quantity of operating fluid within its cylinder at an appreciable pressure for a sufficient time interval to insure the lowering of the trolley after its disengagement from the trolley conductor.

In my present invention, I provide a control valve of a different character which is both positive and reliable in operation and is definitely maintained in its open position after once being actuated thereto, inasmuch as the valve comprises two pistons of different areas which act in conjunction to maintain the valve in a predetermined position after having once been actuated by reason of the resultant pressure upon the pistons.

The single figure of the accompanying drawing is a diagrammatic view of a control system and device embodying my invention.

Referring to the drawing, the system 75 shown comprises a trolley conductor 1, a trolley 2, a pneumatically-released locking device 3, a pneumatically lowered and spring-raised actuating device 4, a release valve 5, an electromagnetically-controlled 80 valve 6 for governing the admission of operating fluid to the pneumatic actuating device 4, an electromagnetically-controlled valve 7 for admitting operating fluid to the pneumatic-release device 3, a control resistor 85 8 and a plurality of manually-operated switches 9 and 10 that are respectively marked "Lower" and "Raise."

The pantograph trolley 2 may be of any 90 well known form and embodies a current-collecting device or contact shoe 13 which is normally adapted to be maintained in engagement with the trolley conductor 1. The pantograph 2 may be conveniently mounted upon the roof of a railway car or 95 electric locomotive, in the usual manner, and may be remotely controlled in a manner to be hereinafter set forth.

The actuating device 4 comprises an operating cylinder 14, having a release opening 14^a near one end thereof, a plurality of pistons 15 and 16 contained therein and respectively attached to a plurality of piston rods 17 and 18 that are pivotally associated

with the arms 2^a and 2^b of the pantograph 2. Surrounding each of the piston rods 17 and 18 and acting upon the respective pistons 15 and 16 are springs 19 and 20 that serve to elevate the trolley 2 and maintain it in engagement with the trolley conductor 1. The pistons are located in the central portion of the cylinder, and intermediate said pistons, an inlet pipe 14^b communicates therewith.

10 The release device 3 comprises a cylinder 21 containing a movable piston 22 provided with a piston rod 23 that is connected to a pivoted latch 24 which serves to engage a 15 detent 25 on the pantograph frame 2 for the purpose of locking said frame in its lowered position. A spring 26 surrounds the piston 23 and serves to maintain the latch 24 in its operative locked position.

20 The release valve 5 merely constitutes an ordinary valve having a handle 27 which is normally maintained in its closed position by a spring 28 and is so located, with respect to the trolley 2, as to be engaged thereby in its lowered position and thereby actuated into its open position to permit the release of operating fluid from the cylinder 14, as will be understood.

25 The electromagnetically-operated valve 6 has a main body portion 32 provided with a plurality of communicating chambers 33 and 34 of relatively different diameters and a movable valve member 35 comprising a plurality of pistons or heads 36 and 37 which are respectively disposed in the chambers 33 and 34. The chamber 33 has a communication to the atmosphere through a port 39 and is also in open communication with a pipe 14^b which is connected to the 30 operating cylinder 14, while the lower chamber 34 is provided with an inlet pipe 41 that conveys operating fluid from a suitable source (not shown) and also with a vent opening 40 in its lower end. The valve 35 member 35 is mechanically associated with a magnetizable core 43 that is provided with an energizing coil 44 by means of which the associated valve pistons 36 and 37 are actuated into their lower positions 35 against the action of a spring 45. In the normal position of the valve member 35, the inlet end of the pipe 41 is covered and closed by the piston 37, as shown in the figure, while the port 39 is left open, thereby permitting any operating fluid in the cylinder 14 to escape.

40 When the operating coil 44 is energized, the valve 35 is moved into its lowered position, and the inlet end of the pipe 41 is uncovered, the exhaust port 39 is closed, and a communication is established between the pipes 41 and 14^b through the valve chambers 33 and 34. After the valve 6 has been operated in the manner set forth to admit 45 fluid to the operating cylinder 14, it is

positively maintained in its open position by the operating fluid acting upon the pistons 36 and 37, the area of and the resultant pressure on the piston 37 being greater than that of the piston 36, thereby 50 maintaining the member 35 in its lowered position and insuring a supply of operating fluid to the cylinder 14 until the same is exhausted by an auxiliary device 5 which operates after the trolley 2 has been actuated 55 to its lowered position as hereinafter set forth.

The valve 7, which is located in a fluid-supply pipe 46 for supplying fluid to the release device 3, is maintained closed by a 60 spring 47 and is opened either manually or by a magnetizable core 49 which is energized by an operating coil 48.

65 The control resistor 8 receives energizing current from the trolley conductor 1 to the trolley 2. A conductor 51 is connected to the resistor 8 at a point 50 to supply low-voltage energy to the operating coils 44 and 48 of the respective valves 6 and 7 through the switching devices 9 and 10.

70 Although I have shown and described my invention as applied to a single trolley of a single car, it is obviously applicable to a multiple-unit train, and, by means of the connections herein shown, a plurality of 75 trolleys upon different train units may be concurrently operated.

75 Assuming the apparatus to occupy the positions shown, the trolley 2, or a plurality of trolleys in the case of a multiple-unit train, may be lowered by closing the switch 9, marked "Lower". This energizes and opens the valves 6 and thereby admits fluid to the cylinder 14 from the supply pipe 41. The pistons 15 and 16 are thus caused to 80 actuate the trolleys 2 into their lowered positions.

85 As soon as the trolleys become disengaged from the trolley conductor 1, the energizing current for the control resistor 8 and the 85 operating coils 44 is interrupted. However, the valves 6 are held open in the manner already described, and the trolleys are brought down, even though their controlling valves 6 are deenergized before the trolleys 90 reach their lowered positions.

95 When the trolleys 2 reach their lowered positions, they are brought into engagement with the handles 27 of the several release valves 5, and said valves are thus opened 100 to permit the escape of operating fluid from the cylinders 14, whereby the pressure within the chambers 33 and 34 of the valves 6 is reduced and the valves are permitted to be returned to their normal closed positions. The relief openings 14^a are also 105 opened to effect a similar function, although this function may be accomplished singly by either of the means referred to.

110 Assuming the trolleys to be lowered, they 115

may be raised in the following manner:—
The trolley on the head car of the train is first raised by manually opening the control valve 7 on the head car and thus unlocking 5 the latch 24 and permitting the springs 15 and 16 to actuate the trolley to its upper position. This supplies energy to the control resistor 8 and, therefore, the remaining trolleys may be raised in the manner here-
10 inbefore set forth by temporarily closing the switch 10 marked "Raise" to electro-magnetically open the valves 7 and the release of the locking devices 3 throughout the remainder of the train.

15 Although I have shown and described my invention as embodying specific circuit connections and structural features, it is evident that many modifications may be effected therein without departing from the spirit 20 and scope of my invention, and I desire, therefore, that only such limitations shall be imposed as are indicated in the appended claims.

I claim as my invention:

25 1. The combination with a pneumatically-lowered trolley adapted to be normally maintained in engagement with a trolley conductor, and a source of fluid under pressure, of an electromagnetically-controlled valve 30 for governing the supply of fluid to the pneumatically-lowered trolley, said valve being adapted to be opened by an electromagnet and to be held by fluid from said source after said magnet is deenergized.
35 2. The combination with a spring-raised pneumatically-lowered trolley normally maintained in engagement with a trolley conductor, of a valve device between said source of fluid and said trolley for governing 40 the supply of fluid thereto and comprising a casing having communicating chambers of different diameters, a piston disposed in each of said chambers, said casing having passageways through the walls thereof normally adapted to be opened and closed by the movements of said pistons, said pistons being rigidly connected together, of different 45 areas and normally adapted to connect said chambers to the atmosphere, and electromag- 50 netic means associated with said movable valve member for actuating the same and causing the pistons to establish communication from the trolley to a fluid-supply source through the valve chambers, said 55 valve device adapted to subsequently maintain said communication.

3. The combination with a spring-raised pantograph trolley, and a pneumatically-actuated device for lowering said trolley 60 comprising a plurality of pistons mounted within a cylinder, said cylinder having an opening for releasing the pressure therein when said pistons reach a predetermined position in said cylinder, of an electromagnetically-operated valve for governing the

admission of operating fluid to said pneumatically-actuated lowering device and adapted to effect the lowering thereof even after the trolley has been disengaged from the trolley conductor, and means associated 70 with said pneumatically-actuated lowering device for releasing the operating fluid from said lowering device when said trolley reaches its lowered position.

4. The combination with a trolley normally maintained in engagement with a trolley conductor, and a fluid-actuated lowering device for said trolley comprising pistons and an operating cylinder, said cylinder having an opening therein near one end 75 thereof for releasing the operating fluid therefrom under predetermined conditions, of a valve for governing the admission of operating fluid to said fluid-actuated device for effecting the lowering of said trolley, 80 and electromagnetic means for actuating said valve for initiating the downward movement of said trolley.

5. The combination with a pantograph trolley and a fluid-actuated device adapted 90 to lower said trolley, of a fluid valve adapted to control the operation of said device comprising a body member having communicating chambers of different diameters, the larger chamber having a supply opening and 95 the smaller chamber an unrestricted exhaust opening and a delivery opening in the walls thereof, a slide valve member disposed in said communicating chambers and constituting pistons of different areas, means for 100 maintaining said valve member in a position to cause the larger piston to cover the supply opening while the exhaust and delivery openings are uncovered and communicate through the valve chambers, and electromag- 105 netic means for actuating said valve member to cause the small piston to cover the exhaust opening and the large piston to uncover the supply opening, whereby communication between the supply opening and the delivery 110 opening is effected through the valve chambers.

6. The combination with a pantograph trolley adapted to engage a trolley conductor, of an operating cylinder having an 115 outlet port near one end thereof, pistons mounted within said cylinder and operatively connected to said trolley for lowering the same, said pistons being adapted to uncover said port at substantially the end of 120 their stroke, means for raising said trolley to an operative position, an electromagnetically-actuated valve adapted to admit fluid to said cylinder comprising a casing having a large and a small chamber, a passageway communicating operating fluid to said large chamber, a passageway extending from said cylinder to said small chamber, a passageway extending to the atmosphere from said small cylinder, piston members 125 130

slidably mounted within said chambers and secured together, said piston members normally adapted to close the passageway into said large chamber and to establish connection from said cylinder to said atmosphere, an electro-magnet for temporarily actuating

said valve for admitting fluid to said cylinder.

In testimony whereof, I have hereunto subscribed my name this 27th day of July 1915.

CHARLES C. WHITTAKER.
